PULP SCREEN AND WASHER

Carl Scheiding, Middletown, Ohio, assignor of
one-half to F. C. Zart, Cincinnati, Ohio

Application December 8, 1939, Serial No. 308,275

3 Claims. (Cl. 92—32)

This invention relates to an apparatus useful in the paper industry for screening and washing paper pulp.

Among the objects of the invention is the provision of a machine of this character which is capable of a higher production per unit area of floor space occupied and embodies continuous operation and automatic plate cleaning.

Referring to the drawings,

Figure 1 is a side elevation of the righthand end of the machine, i. e., that end into which the paper pulp to be screened is introduced.

Figure 2 is a corresponding view of the left end of the machine.

Figure 2a is a full face view of one of the cross-strips of a screening unit, an intermediate portion being omitted;

Figure 2b is a transverse cross-sectional view through the cross-strip of Fig. 2a taken on the line 2b—2b of that figure;

Figure 3 is a plan view of the righthand end of the machine corresponding to Fig. 1;

Figure 4 is a plan view of the lefthand end of the machine corresponding to Fig. 2;

Figure 5 is a transverse cross-sectional view through the machine taken on the line 5—5 of Fig. 2;

Figure 6 is a side view of a screening unit;

Figure 6a is a plan view of the screening unit of Fig. 6;

Figure 6b is an end view of the screening unit of Figs. 6 and 6a;

Figure 6c is a detailed cross-sectional view of one of the two roller-carrying shafts provided at each end of a screening unit;

Figure 7 is a fragmentary plan view of the means for delivering pulp slurry to and spreading it over the screening units;

Figure 7a is a cross-sectional view on the line 7a—7a of Fig. 7;

Figure 8 is a fragmentary plan view of the left-hand end of the machine showing the rotary scraping and residue ejecting means;

Figure 8a is a vertical cross-sectional view through the machine on the line 8a—8a of Fig. 8.

In the drawings, 1 and 2 are substantial pedestals supporting the frame 5 of the machine. The pedestals 1 and 2 support anti-friction bearings 6 and 9. The latter are movable by means of a take-up device 15 for the chain drive by which the position of the shaft 14 of sprocket 132 can be longitudinally shifted. It is, of course, to be understood that there are two similar sprockets upon each side and each end of the machine, making four in all. Over these sprock-

ets a large endless chain, made up of links and rollers 46 and 48, is mounted. There are, of course, two such chains, one traveling over each pair of sprockets, so that each link is in horizontal alignment with the corresponding link on the other chain. Between said chains, screening units or containers 40 are carried, as can best be seen in Figures 3 and 5. As shown in Figures 6, 6a and 6b such screening units are of substantially box-like shape having a foraminous top 88 and a flexible floor 56 slanting toward a bowl shaped discharge port 44 at one end. Each unit is provided with four stepped carrying shafts 45 which shafts are utilized as studs holding the links 46 together. Therefore the units 40 actually form part of their own carrying chain. Figure 6c shows a shaft 45 assembled to carry a roller 48 over which the chain links 46 are fitted. The nuts 50 retain the assembly. Each unit 40 is also provided with a cross strip 51 of rubber or the like to fill the space between the units and thereby to assist in the maintenance of a liquid level of pulp slurry over the continuous platform formed by the series of units 40. As can be seen in Figure 5, the flexible floor of the units is provided with a central metallic plate 59 by means of which the floor may be oscillated.

The oscillating means will now be described. An I beam 68 traverses the machine longitudinally under the middle line of the series of units 40 which together make up what may be termed a screening or filtering conveyor. See Figures 1 and 5. On the I beam is carried a strip 67 to which is fastened a scalloped rack 66. Each unit 40 carries attached to its plate 57 a foot 65 which bears a roller 64, said roller being adapted to fit the scallops of rack 66. Foot 65 comprises a plate 60 carried by two studs 61 which are in turn attached to plate 59 mounted upon the bottom face of the flexible floor 56 and connected through the floor to the plate 57. Plate 60 floats on studs 61 being maintained by a nut threadedly engaging another stud 62 which fits inside stud 61. Springs 63 about each stud 61 press plate 60 downward into engagement with rack 66 by means of roller 64. The high points of rack 66 therefore create a shock resulting in an oscillation transmitted by roller 64, foot 65, plate 60 and springs 63 which decrease the violence of the shock transmitted to plate 57 which is attached to the flexible floor of unit 40, thereby exerting a hydraulic action on the liquid contents of unit 40 and after the manner of a diaphragm pump, pumping the liquid and solid matter up and down through the perforations of the

foraminous plate 88. This action prevents the clogging of the slits or holes of said plate by particles too big to pass through them.

Referring now to Figure 5, 41 is a deflector plate mounted on the deeper side of the interior of a unit 40 so as to depend into the bowl 42 of the discharge port 44. The latter travels within a trough 120 which extends the length of the machine and which is mounted on a bracket 121 carried on an adjustable standard 122 which is bolted to cross beam 12 by means of base 123. Trough 120 is arranged to deliver its liquid contents into screened pulp discharge pipe 126. As can be seen from Figures 5 and 6, there is a small bypass port c in the wall between spout 44 and bowl 42. This allows gradual drainage of small quantities of liquid. Since the container perforations have a greater open area than the discharge opening 44 the contents of the container will always remain inside the latter until the container is tipped when it passes over the sprocket at the discharge end of the machine and then the small quantity of liquid remaining in bowl 42 will be emptied by bypass c. The containers 40, after being inverted to pass through the lower part of the machine on their way back to the starting point will then be substantially empty of liquid although their screens will require cleaning.

Referring again to Figures 1, 2 and 3, it will be seen that the chain of units 40 is drawn along a bar 35 with which the rollers 48 make contact. The bars in turn are supported by brackets 36 which are attached to standards 10 and 11. In this way a flat surface of screens 88 is maintained by preventing the sagging of the chain which carries the screen units 40.

The means employed for delivering and spreading pulp slurry to the screening surfaces 88 will now be described. Referring to Figure 1, 17 is a slurry box to which liquid pulp is being continuously delivered. A dam 19 is provided in this box over which an even flow of slurry occurs. This flow then descends over a cascade seal. The latter comprises an angled body 78 which is hinged to the floor of box 17 by means of hinge 81 and pin 82. A smooth rubber pad 80 extends over the hinge so as to prevent the latter from being clogged with pulp. A rubber sealing apron 79 fits between body 78 and the foraminous surfaces 88 and so assists in maintaining a liquid level over said surfaces. In order to keep the rubber 79 firmly in contact with the surfaces 88, a rod 84 is provided which operates with a hinge 83. The hinge is attached to the rear of body 78 and rod 84 is placed under tension with a spring 86 and handwheel 87 as shown in Figure 7a. Of course, as many rods 84 may be provided as are necessary. Flexible rubber dams 20 and 21 may be provided to settle particles too large to pass the screens 88. The point at which body 78 and its assembly is located is immediately forward of the point at which the filter units 40 come over sprocket 132 to form a level floor. This relation may be seen in Figures 1 and 7a.

Wooden rails or bars 34 are provided to sit snugly at the outer edges of filter surfaces 88 so as to retain a liquid level over said surfaces. As may be seen by Figure 5, a mechanism is provided for adjusting the height of these bars and for locating them into position, once their height has been chosen. Each bar 34 is held by in clamp 32-33 which is in turn associated with a plate 31 upon which the clamp 32-33 is ver-

tically adjustable. The clamp 32-33 together with plate 31 is mounted upon channel plate 16, the enclosed or outer side of which houses the adjusting and locating mechanism 28. As can be seen from Figure 5, the adjusting unit 28 has sliding pads 29 to hold a block 30 which is tapped for a squared-end adjusting screw 27. Shoulders 30b are fitted with gib 29a for vertical movement through said block. Screw 27, after being adjusted vertically with a wrench moves block 30 vertically, thereby lifting or depressing also plate 31, clamp 32-33 and bond bar or rail 34. After suitable adjustment has been reached block 28 is tightened against plate 16 by means of the handwheel and screw. Figure 5 provides the best illustration of this construction. Rail 34 is provided with a water groove w in its lower surface to assist in bonding the bar to the plates 88.

Referring now to Figures 8 and 8a, the machine is provided at its lefthand end (see Figure 2) with a rotary scraper 104 mounted upon a sprocket driven shaft 103. Below said scraper a flexible steel plate 106 ground to a tapered edge makes contact with the traveling screen surfaces 88 so as to shave off from them such oversized nodules of pulp as have not been able to pass the foraminous surfaces 88. Plate 106 is bent up to follow the inclination of an arcuate apron 101 which forms a hump or dam 110 which is integral with a trough 89 in which a helical conveyor 109 is operated by a shaft 108. Scraper 104 operating at high speed throws the nodules shaved off by blade 106 over hump 110 into trough 89 where the rotation of conveyor 109 pushes such material toward a hopper 100 leading out of the machine.

Referring now to Figures 1 and 2, the matter shown here has to do with means of cleaning the surfaces 88 while they are inverted when the units 40 are traveling back to their starting point at the right side of the machine. As can be seen in Figure 11, a trough or apron 111 extends beneath the machine and this trough is supplied with water through a shower pipe 111a. An exit pipe m for refuse water is also provided. A liquid level extending well over the surfaces 88 is however maintained. Toward the left end of the machine there is a trough 112 in which a brush roller 116, supported by bearings 118 and driven by shaft 119, is located. This shaft is driven by a sprocket 136. Baffles 113 and 114 are provided in trough 111 which are so arranged as to provide maximum turbulence in the water. This arrangement can be seen in Figure 1. In brief, a staggered path is provided for the water which flows in one direction above the baffles and in another direction under the baffles through space 115. The flow under the baffles is toward exit pipe m. The rotation of brush 116 as seen in Figure 2 is counterclockwise. Contact of the brush roll 116 effectively removes material from the surfaces 88 which is too fine to have been removed by the blade 106.

Again referring to Figure 5, a screw adjustment is provided which comprises screw 70, nut 71 and socket 75 by which the rack 66 may be withdrawn out of contact with rollers 64. It is therefore possible to regulate the degree of shock produced by the contact of rollers 64 with rack 66 or it is possible to separate these elements entirely so that there is no pumping action through the foraminous plates 88.

As is shown by Figures 2 and 4, sprocket 136, which drives the brush roll, is suitably placed for a motor to drive shaft 119. Drive is then

by chain to sprocket 129 which in turn drives gear 130, meshing with gear 131 which drives sprocket 132. Sprocket 128 is also mounted on shaft 127 which is common to sprockets 129, 128 and gear 130, also drives sprocket 133 which is mounted on shaft 103 which drives rotary scraper 104. A second sprocket 134 on shaft 103 carries a chain drive to sprocket 135, thereby turning shaft 108 to rotate helical conveyor 109.

The operation of my device will be fully apparent from the above description to any competent pulp and paper engineer.

I claim:

1. In a pulp screen washer, a substantially rectangular frame, two sprockets rotatably mounted substantially at the corners of said frame at each end thereof, endless chains passing over opposite pairs of sprockets and adapted to operate in horizontal unison and alignment, a series of screening elements carried between said chains and closely spaced together, a slurry supplying box, a dam in said box and a cascade seal between said box and said series of screening elements, said seal being operative when said screening elements are substantially level, said box, dam and cascade seal being located at that end of the machine away from which the upper series of screening elements moves, means for maintaining a liquid level over said screening elements, a trough extending below said screening elements for discharging filtrate from the latter, a shaving blade, a rotary scraper and a crosswise disposed helical conveyor located behind said blade and scraper at that end of the machine opposite said slurry supplying box, said blade and scraper being disposed in operative relation to said series of screening units when the latter are level, to remove solid matter deposited upon them, said blade being arranged to deliver such solid matter to the scraper, the scraper to deliver it to the conveyor and the conveyor to remove it from the machine; a washing trough adapted to carry a water level and to receive said series of screening elements in inverted position during its traveling back to its starting point, a brush roll in contact with the screening surfaces of said screening elements to wash the latter clear of solid matter clogging their openings and baffle means adapted to create water turbulence beneath the screening units while the latter are being washed and to direct resulting water containing solid matter in suspension back toward that end of the machine which lies under said slurry box.

2. In a pulp screen and washer, a substantially rectangular frame, pairs of identical sprockets at each end of said frame, a common axle for each pair of said sprockets, an endless

chain running the length of the machine connecting opposite sprockets on different axles, a plurality of box-shaped screening elements extending crosswise of and being attached as to their ends to each chain, so as to be carried by said chains in unison while preserving accurate alignment from one chain to the other, flat foraminous surfaces at the top of each screening unit, a discharge spout in the bottom of each screening unit at the lowest point thereof, a deformable strip between each screening unit and the next, said unit being adapted to act as a sealing means, said foraminous surfaces and said sealing units being adapted to cooperate to form a substantially flat surface at some time in the travel cycle of said units, adjustable rail means extending across the ends of the units forming said flat surface, said rails being adapted to maintain a liquid level above said foraminous surfaces as to the sides thereof, a cascade seal at the starting end of said flat surface, pulp spreading and supplying means adapted to supply pulp evenly over said pulp cascade seal, means for removing unfiltered pulp from the other end of said flat surface, means for eliminating pulp so removed from the machine, and a liquid receiving trough extending under said series of screening units when the latter are flatly arranged, the discharge spouts on said screening units extending into said trough, means for removing liquid from said trough and from the machine and washing means including a rotary brush roll for clearing the foraminous portions of said filtering units 35 when in inverted position and traveling towards their starting point to again assume their position as parts of the said flat surface.

3. An individual screening unit adapted to be used in a pulp screen and washer of the character described which comprises a boxlike body, a foraminous flat top for said body, a deformable strip on one longer edge of said foraminous top, a flexible bottom, a stiff plate centrally attached to said flexible bottom, a roller leg extending downwardly from said stiff plate, a spring mounting for said roller leg, a discharge spout at the lowest point of said flexible bottom, a deflector plate adapted to cooperate with said discharge spout to provide a liquid seal, said discharge spout having also in its region where the liquid seal is provided, a small by-pass opening, and attached to the ends of said boxlike body of the screening unit, two stepped shafts protruding from each of the ends of said body, the ends of said shafts being adapted to function as the link studs of a roller chain.

CARL SCHEIDING.
